ADJUSTING MEANS FOR CUTTING STEELS

Joseph H. M. Michon, Toledo, Ohio

Application October 31, 1940, Serial No. 363,782

12 Claims. (Cl. 164—118)

This invention relates to means for effecting lateral adjustment of the cutting steels of metal blanking, trimming and punching machines of that general class shown and described in United States Letters Patent, No. 2,213,919, issued to me on the 3rd day of September, 1940, the present invention being an improvement thereon.

The object of the invention is to provide means whereby after lateral adjustment of the movable member or cutting steel has been effected, the dowel or connecting pin may be removed to permit detachment and resharpening of the cutting steel or for other purposes without disturbing said adjustment.

A further object is to provide cutting steel adjusting means including inner and outer expansible eccentric sleeves and a central locking sleeve adapted to receive a dowel pin, said central sleeve serving to lock the eccentric sleeves in a fixed position of adjustment and the cutting steel and associated parts being removable as a unit from the die shoe so as to obviate the necessity of readjusting the eccentric sleeves when the cutting steel is again positioned on the die shoe.

A further object is to make the dowel of tubular formation with the interior walls at the lower end thereof threaded for engagement with a correspondingly threaded extracting pin so that, by positioning the extracting pin within the dowel and rotating said pin, the dowel will be withdrawn from its socket in the die shoe.

A still further object of the invention is generally to improve this class of devices so as to increase their utility, durability and efficiency.

In the accompanying drawings forming a part of this specification and in which similar numerals of reference indicate corresponding parts in all the figures of the drawings:

Figure 1 is a top plan view of the cutting steel adjusting mechanism embodying the present invention.

Figure 2 is a vertical sectional view.

Figure 2a is a similar view showing the extracting pin within the tubular dowel and said dowel partially withdrawn from its seat within the die shoe.

Figure 3 is a top plan view illustrating another form of the invention.

Figure 4 is a vertical sectional view taken on a horizontal median of Figure 3.

Figure 5 is a vertical sectional view showing how a combination screw and dowel pin can be used in connection with the adjusting mechanism.

Figure 6 is a top plan view of Figure 5.

Figure 7 is a vertical sectional view showing how the extracting pin operates to withdraw or extract a hollow dowel where the adjusting sleeves are not used.

5 Figure 8 is a perspective view of the dowel and extracting pin detached.

Figure 9 is a side elevation of a combined dowel extracting tool and wrench used in connection with the device, and

10 Figure 10 is a modified form of tool.

The improved mechanism forming the subject-matter of the present invention may be used in connection with any type of metal piercing or trimming machine, and in the drawings a portion of a conventional machine is illustrated, in which 5 designates the movable member or cutting steel having a socket 6 formed therein and 7 the lower stationary member or die shoe provided with a seat or socket 8.

15 20 The cutting steel adjusting mechanism comprises an outer longitudinally split eccentric sleeve 9 fitting within the socket 6 and having inner and outer parallel walls, as shown. Fitted within the outer eccentric sleeve 9 is an inner longitudinally split eccentric sleeve 10 having an outer straight wall which bears against the adjacent straight wall of the outer sleeve and provided with an inner tapered wall 11, the lower end of which is threaded, as indicated at 12. The upper ends of the inner and outer expansible eccentric sleeves are formed with a series of circumferential recesses or notches 13 adapted to receive the end of a screw-driver or other suitable tool for rotating the same when it is desired

25 30 35 to adjust the cutting steel laterally with respect to the die shoe. Fitting within the inner sleeve 10 is a central locking sleeve 14 having its outer wall tapered to correspond with the tapered wall 11 of the inner eccentric sleeve and provided at its lower end with circumferential threads 15

40 45 which engage the threads 12 on the inner sleeve, as best shown in Figure 2 of the drawings, so that, after the inner and outer eccentric sleeves have been adjusted to move the cutting die laterally with respect to the die shoe, said inner and outer sleeves will be expanded against the walls of the opening 6 and thus lock said sleeves in a fixed position of adjustment thereby to permit removal of the cutting steel when it is desired

50 55 to resharpen the same without in any manner disturbing said adjustment. The upper end of the locking sleeve 14 is provided with an interior hexagonal socket 16 to permit the sleeve to be rotated with a wrench or other suitable tool to effect locking of the parts. Disposed within the

locking sleeve 14 is a tubular dowel pin 17 having its lower end fitted within the socket of the die shoe and its interior walls at said lower end threaded, as indicated at 18.

As a means for extracting or partially elevating the tubular dowel pin 17 from the die shoe 7, there is provided an extracting pin 19 having its lower end threaded at 20 for engagement with the interior threads of the dowel. The upper end of the extracting pin is provided with an angular head 21 while the lower end thereof is formed with a conical boss 22 adapted to bear against the central portion of the lower wall of the socket 8 so that, by inserting the extracting pin within the tubular dowel and rotating said pin, the hollow dowel may be quickly withdrawn or extracted from its seat in the die shoe. It will thus be seen that, after the parts are assembled, lateral adjustment of the cutting steel with respect to the die shoe may be readily effected by rotating the inner and outer eccentric sleeves and after the proper adjustment has been effected the parts will be effectually locked in said adjusted position by rotating the central locking sleeve. It will, furthermore, be noted that, by inserting the extracting pin 19 within the hollow dowel and rotating said extracting pin, the lower end of the dowel may be elevated to a position above the upper surface of the die shoe 7 so as to permit the cutting steel together with the dowel and adjusting mechanism to be readily slid laterally as a unit off the die shoe without in any manner disturbing the prior adjustment of the parts. After the cutting steel has been removed and resharpened or any other repairs made thereto, said cutting die together with the dowel pin and eccentric sleeves may again be positioned as a unit on the die shoe and the dowel 17 moved to a position within the socket 8 without liability of disturbing the previous adjustment of the eccentric sleeves. This is a decided advantage as in all prior devices, as far as I am aware, after the cutting steel has been removed from the die shoe, further adjustments must be made owing to the fact that the sleeves are not locked in adjusted position prior to removal of the cutting steel.

In Figures 3 and 4 of the drawings, there is illustrated a modified form of the invention, in which the notches 13 in the inner and outer expandable sleeves are omitted and the upper ends of said sleeves formed with angular faces 23 to permit said faces to be grasped by a wrench or other suitable tool to rotate the same. In this form of the device, the upper surface of the cutting steel is cut away, as indicated at 24, to accommodate a wrench when rotating the expandable sleeves. In all other respects the device shown in Figure 4 is similar to that shown in Figure 2 of the drawings.

In Figure 5 of the drawings, there is illustrated another form of the invention, in which a solid dowel 25 is employed, the lower end of which is exteriorly threaded at 26 for engagement with corresponding threads in the socket of the die shoe. In this form of the device, the inner and outer walls of the eccentric sleeves 27 and 28 are preferably tapered and the walls of the socket 29 in the cutting die are correspondingly tapered so as to assist in holding the parts in adjusted position when the central locking sleeve 30 is rotated. The upper end of the dowel 25 is preferably provided with a socket 31 for the reception of a tool to facilitate rotating the same in engagement with its socket in the die

shoe. In this form of the device, the upper ends of the expandable sleeves are preferably formed with notches or recesses 32 for rotating the sleeve, but it will, of course, be understood that the upper ends of said sleeves may be of angular formation if desired.

Figures 7 and 8 of the drawings show how the extracting pin 19 may be employed for removing dowel pins where the eccentric adjusting sleeves are not used. In this form of the device, a hollow interiorly threaded dowel 33 is shown connecting the cutting steel and die shoe, and it will readily be seen that by rotating the pin 19 until the boss 22 contacts with the lower wall of the socket in the die shoe, said dowel pin will be withdrawn from its socket and elevated to a position above the upper surface of the die shoe so as to permit ready removal of the cutting steel to effect resharpening thereof or for other purposes. It will, therefore, be understood that the extracting pin may be used for removing dowel pins regardless of whether the eccentric sleeves are associated therewith or not.

In Figure 9 of the drawings, there is illustrated a combined wrench and dowel pin extracting tool which may be used to advantage in effecting adjustment of the different parts of the device. The tool is preferably formed from a single length of metal having an angular extension 34 constituting a handle and provided with a square terminal 36 forming a wrench. The shank of the tool is exteriorly threaded at 37 for engagement with the interior threads on the hollow dowel pin and is provided with a terminal conical boss 38 adapted to bear against and center the tool within the lower wall of the socket in the die shoe, as will be readily understood. A different form of tool is illustrated in Figure 10 of the drawings, in which the shank of the tool is threaded at 39 and the upper end thereof formed with a countersunk socket 40 constituting a wrench head.

It will be noted that by employing an interiorly threaded tubular dowel and extracting pin in connection therewith, it is not necessary to extend the opening for the dowel pin entirely through the die shoe to permit removal of the dowel as is generally the case as the lower end of the extracting pin, by engagement with the center of the tapered bottom wall of the socket in the die shoe, will effectually elevate and remove the dowel from the die shoe without the necessity of introducing a releasing tool through the bottom of the die shoe to effect the removal of the dowel as is now generally the case.

It will thus be seen that there is provided simple and compact means whereby any desired lateral adjustment of the cutting steel with respect to the die shoe can be effected and the parts locked in a set position of adjustment to permit removal and replacement of the cutting steel without disturbing or in any manner affecting said adjustment, thereby not only facilitating and expediting work on metal cutting and bending machines but also reducing cost of such work to a minimum.

From the foregoing description, it is thought that the construction and operation of the device will be readily understood by those skilled in the art and further description thereof is deemed unnecessary.

Having thus described the invention, what is claimed as new is:

1. The combination with relatively stationary and movable members, of an adjusting device in-

cluding inner and outer eccentric sleeves mounted on one of said members for adjusting the movable member laterally with respect to the stationary member, and a dowel receiving locking sleeve engaging the adjacent eccentric sleeve for holding said eccentric sleeves in adjusted position when the stationary and movable members are separated.

2. The combination with relatively stationary and movable members, of an adjusting device including inner and outer eccentric sleeves mounted on one of said members for adjusting the movable member laterally with respect to the stationary member, a dowel connecting the stationary and movable members, and a locking sleeve interposed between the dowel and the inner eccentric sleeve for locking said sleeves in a set position of adjustment.

3. The combination with relatively stationary and movable members, of an adjusting device including inner and outer expansible eccentric sleeves mounted on the movable member for adjusting said movable member laterally with respect to the stationary member, a dowel connecting the stationary and movable members, and a locking sleeve interposed between the dowel and inner eccentric sleeve for locking said sleeves in a set position of adjustment, said movable member, eccentric sleeves, locking sleeve and dowel being removable as a unit from the stationary member without affecting the adjustment of said eccentric sleeves.

4. The combination with relatively stationary and movable members, of an adjusting device including inner and outer expansible eccentric sleeves mounted on one of said members for adjusting the movable member laterally with respect to the stationary member, the inner eccentric sleeve being tapered and provided with a threaded portion, a dowel connecting the stationary and movable members, and a locking sleeve interposed between the dowel and the inner eccentric sleeve and provided with threads engaging the threads on said inner sleeve for holding said sleeves in adjusted position when said stationary and movable members are separated.

5. The combination with relatively stationary and movable members, an adjusting device including inner and outer expansible eccentric sleeves mounted on one of said members for adjusting the movable member laterally with respect to the stationary member, the inner wall of the inner sleeve being tapered and provided with threads, a hollow dowel connecting the stationary and movable members and provided with interior threads for engagement with an ejecting pin, and a tapered locking sleeve receiving the hollow dowel and provided with threads engaging the threads on the inner eccentric sleeve for holding both sleeves in adjusted position when the stationary and movable members are separated.

6. The combination with relatively stationary and movable members, one of which is provided with a socket and the other with a seat, of an adjusting device including inner and outer expansible eccentric sleeves mounted in said socket, a locking sleeve having threaded engagement with the inner eccentric sleeve for holding said sleeves in a set position of adjustment, the upper portion of the locking sleeve being provided with a tool receiving socket, and a tubular dowel extending through the locking sleeve and engaging said seat.

7. The combination with relatively stationary

and movable members, of an adjusting device mounted on one of the members and including longitudinally split nested eccentric sleeves, one of which is tapered downwardly and provided with threads, a centrally disposed tapered locking sleeve having its lower portion threaded for engagement with the threads on the adjacent eccentric sleeve for locking said sleeves in a set position of adjustment, the upper portion of the locking sleeve being provided with a tool receiving socket, a hollow dowel fitting within the locking sleeve and connecting the stationary and movable members, the interior walls of said dowel being threaded for engagement with a correspondingly threaded dowel ejecting tool.

8. The combination with relatively stationary and movable members, of an interiorly threaded hollow dowel connecting said members, and an ejecting pin having threads engaging the threads on the dowel and adapted to bear against the stationary member for ejecting said dowel when the pin is rotated.

9. The combination with relatively stationary and movable members, one of which is provided with an opening and the other with a seat registering therewith, of a hollow dowel fitted in said opening and seat and connecting said members, the interior walls of the dowel at the lower end thereof being threaded, and an ejecting pin provided with threads for engagement with the threads on the dowel and having its lower end provided with a substantially conical boss adapted to bear against the bottom wall of said seat for ejecting the dowel when said pin is rotated.

10. The combination with relatively stationary and movable members, of an adjusting device including inner and outer longitudinally split eccentric sleeves mounted on one of said members for adjusting the movable member laterally with respect to the stationary member, a central locking sleeve having threaded engagement with the inner eccentric sleeve for holding said eccentric sleeves in a set position of adjustment when the stationary and movable members are separated, a hollow dowel extending through the locking sleeve for connecting the stationary and movable members, said dowel being provided with interior threads, and an ejecting pin engaging the threads on the dowel and bearing against the stationary member for elevating the dowel, the eccentric sleeves, locking sleeve, dowel and ejecting pin being movable together as a unit with the movable member when said members are separated.

11. The combination with relatively stationary and movable members, of an adjusting device including nested eccentric sleeves mounted on one of said members, a dowel connecting the stationary and movable members, and a locking sleeve interposed between the dowel and the adjacent eccentric sleeve for locking said sleeves in a set position of adjustment, the movable member and its associated parts being removable as a unit from the stationary member without affecting the adjustment of said eccentric sleeves.

12. The combination with relatively stationary and movable members, of a hollow dowel connecting said members, and means operable within the hollow dowel and coacting with the stationary member for ejecting said hollow dowel when downward pressure is exerted on the ejecting means.
